UNITED STATES PATENT OFFICE

2,373,966

TYPE CHASE

Frederick Kohnle, Dayton, Ohio, assignor to The Monarch Marking System Company, Dayton, Ohio, a corporation of Ohio

Application January 9, 1943, Serial No. 471,839

1 Claim. (Cl. 101—393)

This invention relates to type chases. More particularly the invention relates to improvements in that character of chase especially useful in tag marking or printing machines. In this type of machine, it is desirable that the type or printing characters be readily interchangeable for conveniently varying the price marking or printing setup.

The type chases of price marking machines are supplied to order. That is to say, the chase in each case is arranged with the type set as required by the particular department store. Accordingly, each machine has necessarily been special as to the chase structure. Mainly, it has been the object here to provide universal parts adapted to be assembled to order.

The concept here is the result of study of the problem of construction involved in designing a chase so that it will receive and support the lines of type in a relatively wide range of sizes with type of varied size usable in any given setup. In this study, it has been the objective of the inventor to provide a chase for interchangeable type wherein the size of the type receiving openings or sockets may be readily altered or modified to accommodate for type of different "point," as for example, the sizes used conventionally in marking price tags. This permits the use of a larger or more prominent type for the price as opposed to the type employed for the other indicia printed on the same tag.

Attention is directed to the present inventor's previously issued Patent No. 2,251,227, issued July 29, 1941, disclosing and claiming an improved type chase. In this patent just referred to, the chase provides demountable type supporting bars, which are readily adjustable as to spacing, that is to say, bars which may be disposed either very close or very far apart, accommodating, for example, either six point, nine point, or fourteen point type. Thus, each type supporting bar may be separately removed or replaced without disturbing the adjoining bars. Moreover, each of these bars may provide differently spaced lateral supporting means for the type so as to vary the spacing in the rows.

It has been the further object of the present inventor to provide an improved means for locking the type supporting bars in position. This means is a permanent part of the type chase frame and preferably is hinged so as to be displaced from a position holding the bars in position to a release position where the bars may be easily and quickly removed and rearranged as desired. Thus, the inventive concept present in

this case is concerned with the provision of a further improved means for accomplishing the general purposes set out in the previously issued patent.

Other objects and certain advantages of the invention will be more fully apparent from a description of the drawing in which:

Figure 1 is a perspective view of the improved type chase of this invention.

Figure 2 is a top plan view showing the locking means in position for holding the type bars in position.

Figure 3 is a view taken similar to Figure 2 but showing a different arrangement of the supporting bars for supporting lines of type of a different point.

Figure 4 is a view taken similar to Figure 3 showing the further arrangement of the supporting bars but also illustrating the locking means 20 displaced for convenient removable of the type supporting bars.

Figure 5 is a sectional view taken on line 5—5, Figure 2, illustrating a supporting bar of the form shown in this particular view.

Figure 6 is a sectional view taken on line 6—6, Figure 3, detailing the mounting and fastening of the locking device.

Figure 7 is a view taken on line 7—7, Figure 3, illustrating a supporting bar of Figure 3.

Figure 8 is a sectional view taken on line 8—8, Figure 4, illustrating the locking means in released position.

Figure 9 is a side view of one of the supporting bars of Figure 4.

Figure 10 is a fragmentary sectional view taken lengthwise of the chase showing type supported in position from the supporting bars.

Referring to the drawing, the rectangular frame of the chase is generally indicated at 11. The frame or casing is made up of four plate elements, side walls 12 and end walls 13 respectively. The side walls are flat plate structures notched as will be described hereinafter. The end plates include top flanges 14 and side flanges 15. These flanges are turned outwardly and the side flanges 15 are welded or otherwise secured to the side plates 12. The top flanges 14 provide the means for mounting and securing the type supporting bar locking means, as will be more apparent later in this description.

The cross plates or supporting bars 16 engage with the side plates 12 in a manner depending upon which plates are being utilized. To provide for variation in the spacing of these supporting plates, the side plates 12 are notched as follows.

Each plate includes a series of vertical notches 17 cut into the upper edges of the plates and extending about one-third of the height of the side plates. As indicated in Figure 5, the type supporting cross plates or bars engageable in these notches include laterally extended tenons 18 which fit within the notches for supporting the plates with their edges flush with the upper and lower edges of the casing respectively. In addition to these notches, which are cut entirely through the side plates, another supporting structure is provided in the form of vertical grooves 19 extending down the inner faces of the side plates. (Note particularly Figure 6.) The supporting bars cooperating with these grooves (Figure 7) also include tenons or extensions 20 which fit within the grooves 19 for supporting the particular plates with their upper and lower edges flush with the upper and lower edges of the casing or supporting box structure.

As will be apparent from Figure 6, the notches 17 are spaced at greater distances than the grooves 19. Although there may be some overlap of these grooves and notches, this is unimportant since the grooves 19 extend throughout approximately two-thirds of the height of the side plates. As shown in Figure 1, a given type setup may include some of each style of cross plate.

One side of each cross plate or partition includes a series of parallel vertical grooves 21 appropriately spaced for receiving the type elements. Each type element 22 (Figure 10) has a longitudinal rib or fin 23 at one side thereof. These grooves 21 do not extend entirely to the bottoms of the respective plates and the fins are component so that the type elements are suspended as shown in Figure 10. The spacing of the grooves along the face of the cross bars is appropriate for the point size of type employed. As stated, these cross plates, or a mixture of both forms or all of one, are assembled within the casing to provide a selected number of type receiving sockets 24. Each socket receives a line of type of different point size.

In order to secure the cross plate assembly within the casing, locking means is provided. This means consists of a swinging latch element 25 pivoted on the top flange 14 of one end plate of the casing. The pivotal mounting is through a pin 26 fixed within the flange and having an enlarged head 27 securing the latch in swinging position. The vertical flange 28 of the latch en-

gages against the side plate of the casing when the latch is swung into latching position. At this point, an extension 29 of the latch overlies an extension 30 of the flange 14 at the other end of the casing. A screw 31 is provided. This screw has an enlarged knurled head 32 and engages through a clearance aperture 33 in the latch and incorporates a threaded portion screwed into a screw threaded aperture 34 in the extension of the flange 14. Latching is accomplished by means of the longitudinally extended flange 35 of the member 25 which overhangs adjacent ends of all of the inserted cross plates.

The drawings illustrate four different arrangements for price marking setups. Specifically, Figure 1 provides an arrangement of cross plates wherein both styles are used and the chase then carries type of two different point sizes. Thus, about half of the chase of Figure 1 will receive, for example, type of six-point size and half, for example, of nine-point size.

In Figure 2, all of one style of supporting bar is employed and thus there exists a uniformly spaced set of sockets for receiving type of the intermediate size, for example, nine-point.

In Figure 3, the cross bars are all of the type engageable with the internal grooves and, therefore, the chase accommodates six-point type throughout.

In Figure 4, the supporting bars of Figure 3 are placed in alternate grooves. This omission of bars makes it possible to accommodate fourteen-point type. The overlap of the flange 35 is sufficient for retaining or locking in position any arrangement of either type of supporting bar.

Having described my invention, I claim:

A type chase comprising a frame of rectangular form, opposite side walls of said frame being notched the notches extending vertically and being formed in the upper edges of the walls, a series of oppositely disposed vertical grooves in the inner faces of said opposite side walls of the rectangular frame, the spacing between said grooves being different from the spacing of said notches and said grooves extending below said notches in the side walls, and a series of type supporting plates adapted to be disposed cross-wise in the frame, said plates having tenons fitting the notches and grooves whereby different sizes of type may be disposed between the plates.

FREDERICK KOHNLE.
